ELECTRONIC VIEW FINDER

Richard L. Campbell, Maywood, N. J., assignor to
Allen B. Du Mont Laboratories, Inc., Passaic,
N. J., a corporation of Delaware

Application January 10, 1942, Serial No. 426,321

5 Claims. (Cl. 178—6.8)

This invention relates to a view finder that is particularly useful in connection with television cameras. By this invention a television camera man can monitor the scenes or objects which are being transmitted while panning and focusing the pick-up camera. The image which is observed in the view finder is upright and can be made appreciably brighter than is possible with optical means. It can be used with different sorts of television cameras now known.

In carrying out this invention the view finder is made up as a small monitoring unit in compact form that is adjustably mounted upon the camera itself in such a location that it can be conveniently adjusted and watched by the camera man as he operates the camera. Scanning and video signals are fed to the view finder from the control unit that is provided for the camera itself so that the camera man has instantly the information that is being transmitted and can quickly make adjustments that may be needed for obtaining better results. The view finder circuits may be controlled in common with and simultaneously with the camera.

The invention may be understood from the description in connection with the accompanying drawing, in which:

Fig. 1 is a perspective view showing a camera and view finder mounted upon a tripod;

Fig. 2 is a block diagram illustrative of the invention; and

Fig. 3 is a diagram of electrical connections to the camera and view finder.

In the drawing, reference character 1 indicates a tripod with a universal joint 2 by means of which the camera 3 is mounted upon the tripod and can be turned to different positions by means of the handle 4. The camera is provided with a lens that is focused by means of the handle 6 in the well known way.

The view finder 9 is connected to the camera 3 by a connection 10 in such a manner that it is swung around with the camera as the camera is turned for panning the scenes, while at the same time the view finder can be turned about this connection 10 so as to be adjusted to different positions in a plane parallel to the sides of the camera 3. The controls for the view finder may be mounted thereon. A light shield for the view finder is shown at 11.

A generator for synchronizing pulses is diagrammatically indicated at 19 in Fig. 2. Leads 20 and 21 for horizontal and vertical sweeps extend from generator 19 to the camera control unit 22, comprising camera sweeps, view finder 55 way.

sweeps and main video amplifier, from which the lead 23 extends to carry the output picture signals.

A lead 24 applies the video signal from the video amplifier to the supply unit 25 for the view finder 9, and power is also supplied to this view finder supply unit 25 by means of the lead 26 which may lead, for example, from a source of 110 volt alternating current. A power and video signal cable 10 27 leads from the unit 25 to the view finder 9.

A cable 30 for carrying the camera sweep signals, the camera video signal, the view finder sweeps and other control wires is connected between the unit 22 and the camera 3. Lead 32 15 applies the horizontal and vertical sweeps to the view finder 9 to which the power and the video signal are applied by the cable 27. Sweep voltages are thus fed from the camera control unit 22 through the camera cable 30 and lead 32 to the 20 view finder 9. When an iconoscope camera is used, keystoning, and the use of circuits operating magnetically militate against using the camera sweep for the view finder; therefore the sweep circuits for the view finder 9 are brought directly 25 from the cable 30 as indicated by the dotted line. The isolating stages for the view finder are energized from the sweep input circuits 20, 21 of the camera control unit 22, which are fed from the synchronizing generator 19. This is not necessary with an orthicon camera since there is then no keystoning, so that the view finder sweeps can be connected to the camera sweep lines.

The connections for the view finder are shown in more detail in Fig. 3. The horizontal sweep signal from lead 32 (Fig. 2) is applied to the output stage 42, from which it is applied by leads 38 to the horizontal deflection plates 39 of the cathode-ray tube 40 that is located in the view finder 9 (Fig. 1). A five inch intensifier type cathode-ray tube has been found to be very suitable as a view finder. The vertical sweep circuit signal, also from lead 32 (Fig. 2), is applied to the output stage 43 (Fig. 3), from which it is applied by leads 44 to the vertical deflection plates 45. The video signal from the camera 3 (Fig. 2) is applied to the video amplifier 46 (Fig. 3) and thence by lead 47 to the control grid 48 of the tube 40 of the view finder 9. The other elements of the gun structure of the tube 40 with their control circuits are of the well known sort and are shown somewhat diagrammatically in Fig. 3 without detailed description thereof. The resistor network 49 is indicated for applying suitable voltages to gun elements in the usual

This invention has been found to be practical in actual use, due, among other things, to the facts: that an intensifier type of cathode-ray tube 40 is used so that sufficient brightness can be made to appear upon the screen, thus enabling one to use the view finder 9 where there is very strong light such as direct strong sunlight or high intensity studio lighting; electrostatically controlled deflection is used so that straight amplifiers can be used for applying the sweep to the cathode-ray tube in the view finder; vertical and horizontal sweeps for the view finder are controlled from the same voltage sources that are applied to the camera sweeps, thus eliminating the necessity for additional synchronizing circuits; the video signal that is controlled from the output of the camera chain provides permanent monitoring of the camera circuit on which the view finder is being used; power is furnished to the view finder from a source which is physically separated from the camera 3 so that stray magnetic fields are avoided and a source of power with its attendant weight does not have to be carried by the camera; and the controls for the video, for the sweeps, and for the cathode-ray tube are mounted on the view finder so that they are in convenient reach of the camera man. The video signal for the view finder 9 is obtained from an output amplifier in the camera control and is fed over a coaxial cable to the view finder supply unit 25 where it can be amplified and from which it is fed to the view finder which has an amplifier 46 for driving the cathode-ray tube 40 in the view finder.

What is claimed is:

1. A television pick-up camera, a view finder adjustably mounted on said camera, a control unit for said camera, a view finder supply unit, and means for feeding scanning and video signals from said control unit to said view finder, said last named means comprising a lead from

said camera to said view finder, a lead from said control unit to said view finder supply unit and a lead from said view finder supply unit to said view finder.

5. A television pick-up camera, a view finder mounted on said camera, a control unit for said camera, means comprising leads for feeding scanning and video signals from said control unit to said view finder, a supply unit for said view finder, and leads connecting said supply unit to said view finder and said control unit.

10. A television pick-up camera, a view finder mounted on said camera, a control unit for said camera, sweep circuit connections from said control unit to said view finder, and means comprising a lead from a power supply unit and a lead from said control unit to said supply unit and a lead from said supply unit to said view finder, to supply power and video signals to said 20 view finder independently of said sweep circuit connections.

15. A television pick-up camera, a view finder mounted on said camera, a control unit for said camera, a view finder supply unit, and means 25 for feeding scanning and video signals from said control unit to said view finder, said last named means comprising a lead from said camera to said view finder, a lead from said control unit to said view finder supply unit and a lead from 30 said view finder supply unit to said view finder, said view finder being provided with an intensifier for increasing the brightness of the picture on the screen thereof.

20. A television pick-up camera, a view finder mounted on said camera, a control unit for said camera, means for feeding scanning and video signals from said control unit to said view finder, leads connecting said supply unit to said view finder and said control unit and a power supply 40 for said view finder independent of said camera.
